(57) **CLAIM**

The ornamental design for a matcha bowl, as shown and described.

DESCRIPTION

FIG. 1 is the perspective view of a matcha bowl, showing my new design;
FIG. 2 is the front view of a matcha bowl thereof;
FIG. 3 is the right view of a matcha bowl thereof;
FIG. 4 is the top view of a matcha bowl thereof;
FIG. 5 is the bottom view of a matcha bowl thereof;
FIG. 6 is another side view of a matcha bowl thereof; and,
FIG. 7 is another side view of a matcha bowl thereof.
The broken lines in the drawings depict portions of the Matcha Bowl that form no part of the claimed design.
